SLEEPING GARMENT WITH ATTACHED
SHAPED FEETSamuel M. Kephart, Roanoke, Va., assignor to
Puritan Mills, Inc., a corporation of Virginia

Application February 14, 1949, Serial No. 76,278

3 Claims. (Cl. 2—83)

1

This invention relates to a sleeping garment of the bifurcated type, either in one piece (union) style or the equivalent two piece style with the nether and upper parts detachably fastened and having attached shaped feet. Such garments are generally full in the legs and foot portions to permit easy donning of the garment and in the interest of bed comfort.

In the conventional garment of this type the child's feet readily slip out of the foot portion during sleeping, so that the vacant foot portions become folded over the occupied leg portions or twist relative thereto, closing the lower ends of the leg portions whereby when the child stretches, the feet are uncomfortably cramped. Furthermore, when the child gets out of bed, he walks on the leg portions, the vacant foot portions dragging, resulting in soiling the leg portions and creating the hazard of tripping.

The general object of the present invention is to provide a garment of the type described having the passage between the leg and foot portions amply adequate to admit the foot, and having restricting means about the ankle effective to retain the foot within the foot portion without constricting the ankle of the wearer.

Another object of the invention is to provide a garment as described, with surplus length in the legs to provide for growth, the fullness incident to the extra length blousing over the restricted angle zone.

Other objects of the invention will appear as the following description of several practical embodiments thereof proceeds.

In the drawings which accompany the following specification:

Figure 1 is a perspective view of a sleeping garment embodying the principles of the invention;

Figure 2 is a side elevation of one of the leg and foot portions of Figure 1, partly in section;

Figure 3 is a side elevation showing a modification of the invention;

Figures 4, 5 and 6 are similar views, partly in section showing alternative restricting means.

Referring now in detail to Figures 1 and 2, the numeral 1 represents a sleeping garment having shaped foot portions 2, attached to the ends of the leg portions 9. The foot portion, as shown, is formed of four parts, two front pieces 3 and 4 stitched together in a middle seam from toe to ankle, a single heel piece 5 bent about the back of the foot and stitched to the back edges of the front pieces forming seams 6, preferably perpendicular to the plane of the sole, and the sole piece 7 stitched to the lower edges

of the front and heel pieces 3, 4 and 5. The sole piece may be of double thickness, if desired, as shown at 8 in Figure 2, in which case the outer layer may be of wear resisting and preferably slick material so that it will not collect dirt.

The construction of the foot portions is substantially the same in all of the illustrated forms of the invention, but the latter is not committed to any particular construction of shaped feet. The advantage of the shaped foot is that when the child is lying down, his foot lies flat against the sole which is substantially at right angles to the axis of the leg portion 9, so that when the foot is thrust downward there is no component of force tending to push the toes into cramped position in the front end of the foot portion.

The seams 6 of the foot portion preferably coincide with the side seams 10 of the leg portions.

It will be noted in Figures 1 and 2 that the part of the leg portion forward of the side seams 10 is somewhat longer than the rearward part of the leg portion, the end edges of the respective portions being shown at 11 and 12, in Figure 2. Both parts of the leg portion are full down to the edges 11 and 12. The foot portion is stepped in height complementary to the leg portion, that is, the front of the foot portion is shorter than the rearward part of the foot portion. The foot portion is stitched to the leg portion substantially along the edges 11 and 12, the fullness of the leg portion extending lower at the front than at the rear. A reinforcing band 13 is provided, which is wide enough to embrace the circumferential zone defined by the edges 11 and 12. This band is stitched both at its upper and lower edges to both the leg and foot portion as far forward as the side seams 10, and anterior to said side seams it extends in the form of free tabs 14 and 15. These may be buttoned together or otherwise secured, and are of such length when fastened as to constrictively embrace the gathers of the front part of the leg portion which they overlie. The circumference defined by the band 13 when the tabs are secured together, defines an ankle opening in the garment which is larger than the child's ankle, so as to avoid any constriction of the ankle, but small enough to prevent the foot from escaping from the foot portion.

The advantage of having the fullness of the leg extend lower at the front than at the back is that a larger passage is thereby provided for the entrance of the foot into the foot portion when the tabs are unsecured.

Referring now to Figure 3, the form of invention thereby illustrated differs from that above described, in that the forward and rearward parts of the leg portion of the garment terminate in the same plane, and that the top of the foot portion is of uniform height. The band 13 is entirely on the foot portion and does not overlie any of the fullness of the leg portion, but by drawing in upon the foot portion when the tabs 14 and 15 are brought together, it constricts the foot portion of the ankle zone and accomplishes the same result as does that form of the invention shown in Figures 1 and 2.

Figures 4, 5 and 6 show forms of the invention in which the leg and foot portions are united in the same transverse plane, and in which the restricting means is superposed upon the foot portion. In Figure 4 a wide band of elastic 16 circumscribes the rearward part of the foot portion, having its end stitched in the side seams 6. This band is housed in a tubular seam formed by the overlying strip 17, which is stitched at its upper and lower edges to the rearward part of the foot portion and embraced in the side seam 6. The tabs 14 and 15 may be a continuation of this piece. The elastic band 16 is of such length that when the tabs 14 and 15 are buttoned, the ankle opening is small enough to retain the foot in the foot portion without imposing any constriction upon the child's ankle, the elastic band being at the same time long enough to stretch under the pressure of the heel, to permit the foot to be withdrawn without releasing the tabs. The fullness of the leg portion expands with the expansion of the ankle opening in the top of the shoe, so as to make it extremely easy for the garment to be donned, the tabs being preferably unfastened at this time.

In Figure 5 a tubular seam 18 extends completely about the foot portion, said seam enclosing a circular wide elastic band 19, capable of expanding to admit the foot, and of contracting to prevent the involuntary withdrawal of the foot from the foot portion, and of such a length as to cause the garment to be a free fit with respect to the wearer's ankle.

In Figure 6, the general construction is the same as in Figure 5, but in this case a drawstring is within the tubular seam 18, the ends of which emerge from an opening in the front of said seam.

In all of the illustrated variants of the invention the same general inventive concept is present, of having a sleeping garment in which there is normally ample fullness to permit the feet to be readily inserted through the legs into the foot portions of the garment, even by the most inexperienced and juvenile dresser, and providing means which without constricting the wearer's ankle, restricts the ankle zone between the leg and foot portions to such an extent as to prevent the foot from involuntarily escaping from the foot portions during sleep or in the act of walking. In all forms it is contemplated to make the leg portions of extra length with respect to the rated size of the garment, to allow for one or two years' growth, the surplus length causing the leg portion to blouse over the relatively stable zone defined by the ankle band.

While I have in the above disclosure described what I believe to be practical embodiments of the invention, it will be understood by those skilled in the art that the specific details of construction and arrangement of parts, as shown and described, are by way of example and not

to be construed as limiting the scope of the invention.

What I claim as my invention is:

1. Sleeping garment including a leg portion having inner and outer side seams, the end of said leg portion having the part forward of said seams longer than the part rearwardly of said seams, a shaped foot portion attached to the end of said leg portion having its adjacent end of complementary shape to that of said leg portion, said leg portion being full and gathered at its line of juncture with said foot portion, the normal girth of the passage between said leg and foot portions being large enough to admit the foot to said foot portion, a restricting ankle band circumferentially stitched to the rear of said foot portion from one to the other of said side seams, said band having forward tab extensions embracing the gathered forward part of said leg portion, and means for fastening said tabs together to reduce the girth of said passage sufficiently to prevent the withdrawal of the foot from said foot portion.

2. Sleeping garment including a leg portion having inner and outer side seams, the end of said leg portion having the part forward of said side seams longer than the part rearwardly of said side seams, a shaped ungathered foot portion attached to the end of said leg portion having its adjacent end of complementary shape to that of said leg portion, the latter being full and gathered at its line of juncture with said foot portion, the normal girth of the passage between said leg and foot portions being large enough to admit the foot to said foot portion, a restricting ankle band stitched to the rear of said foot portion through an arc extending on both sides toward said side seams and extending about the gathered part of said leg portion for reducing the girth of said passage sufficiently to prevent the withdrawal of the foot from said foot portion.

3. Sleeping garment including a leg portion, a shaped foot portion substantially of ankle height attached to the end of said leg portion, the latter being gathered at its line of juncture with said foot portion and forming therewith a passage sufficiently capacious to admit the foot of the wearer to said foot portion, the latter at said line of juncture being ungathered, an ankle encircling band at said line of juncture stitched circumferentially about the rear of said foot portion to substantially the middle of the sides of said line of juncture, extending forwardly free from the front of said foot portion, adapted to be secured in restricting relation about the front of said foot portion sufficiently to prevent the withdrawal of the foot from said foot portion.
